UNITED STATES PATENT OFFICE.

JAMES STRATTON AND WILLIAM J. STRATTON, OF BROOKLYN, NEW YORK.

NIGHT-LIGHT.

SPECIFICATION forming part of Letters Patent No. 352,718, dated November 16, 1886.

Application filed May 10, 1886. Serial No. 201,711. (No model.)

To all whom it may concern:

Be it known that we, JAMES STRATTON and WILLIAM J. STRATTON, of Brooklyn, in the county of Kings and State of New York, have 5 invented a new and Improved Night-Light Attachment, of which the following is a full, clear, and exact description.

Our invention relates to the construction of a night-light attachment, the object of the invention being to provide an adjustable device whereby the light from a small lamp or gas-burner may be directed on any desired object in the room—such, for instance, as the clock—the light being shaded so as to leave the rest 15 of the room in comparative darkness.

To the end named the invention consists in the peculiar construction and arrangement of parts, as will be hereinafter fully described, and pointed out in the claims.

Reference is to be had to the accompanying drawings, forming a part of this specification, in which similar figures of reference indicate corresponding parts in all the figures.

Figure 1 is a side view of our improved attachment, representing the same as arranged in connection with a drop-light attachment, the screen and the lens being shown in central vertical section. Fig. 2 is a side view of the apparatus arranged to be used in connection 30 with a small lamp, and Fig. 3 is a diagram illustrating the manner in which the device illustrated in Fig. 1 is applied in practical use. Fig. 4 is an end view of the attachment shown in Fig. 1.

Referring now to the general construction illustrated in the drawings, 10 represents a lens the convex face of which is shaded by a hood, 11, said hood being formed with a groove, 12, within which the edge of the lens 40 is held. The lens and its hood are supported by a short standard, 13, which standard is carried by a coupling-piece, 14, arranged in connection with the tube 15 of a drop-light socket, 16, the parts being united by a swing-joint, 45 40, of ordinary construction. The gas is led through a tube, 17, to a burner, 18. Upon the burner 18 there is arranged a two-part screen, 20, consisting, essentially, of a cylindrical section, 21, to one side of which there is secured 50 a cone-shaped section, 22, the parts being so arranged that the rays of light from the burner 18 will be free to fall upon the lens, but all other rays, except those passing out through the top of the section 21, will be intercepted.

55 In Fig. 2 the tube 17, instead of carrying a

burner, 18, is provided with a lamp-stand, 30, upon which there is secured a lamp, 31, the lens, the lamp, and its screen being all carried by a swing-joint, 33, formed in connection with the standard 50, upon which the 60 whole apparatus is mounted.

In Fig. 3 we illustrate the manner in which the attachment is employed when a gas-jet is used for the purpose of producing the light—that is, we show how the rays of light may 65 be directed upon the clock or any other object in the room.

It will be seen that as the lamp or burner, as well as the lens, is supported by a swing-joint the parts may be moved so as to throw 70 the rays at any elevation desired.

The interior of the section 22 is blackened, so as to present a non-reflecting surface, the idea being to prevent the production of rings in the light thrown by the lens.

We are aware that a camera has been connected by a ball-and-socket joint to a gas-burner, said camera being provided at one side of its interior with a reflector, and at the side opposite the reflector with a lens and conical 80 tube for emitting the light and throwing it to any desired point; and we are also aware that reflectors have been secured to gas-burners, and therefore do not claim such inventions.

Having thus fully described our invention, 85 what we claim as new, and desire to secure by Letters Patent, is—

1. The combination, in a night-light, of a support formed with a swinging joint, a burner, a screen supported thereon and formed of a 90 cylindrical section and a lateral cone-shaped section, and a lens supported by the swinging joint in front of the cone-shaped section of the screen, substantially as shown and described.

2. In a night-light attachment, the combination, with a drop-light, of the screen 20, composed of the cylindrical section 21 and the cone-shaped section 22, and supported upon the burner, the standard 13, projecting from a joint in the drop-light, the hood 11, secured to the standard in front of and a short distance from the cone-shaped section of the screen, and the lens 10 in the said hood, substantially as herein shown and described.

JAMES STRATTON.
WILLIAM J. STRATTON.
